UNITED STATES PATENT OFFICE

SAMUEL E. SLONIMSKY, OF CHELSEA, MASSACHUSETTS

AIRPLANE PROPELLER

Application filed November 23, 1931. Serial No. 576,774.

This invention relates to and has for an object the provision of an improved type of airplane propeller of the same general character and for the same general purpose as that described and claimed in my pending application for patent filed May 21, 1929, Ser. No. 364,805.

The principal object of the invention disclosed in this application is to provide a mechanism attachable to an airplane motor for operatively supporting and connecting the propellers with the motor in such a manner that a pilot during the flight of a plane may change the pitch of the propeller blades to selected angles or to neutral position, or reverse the blades at will while the plane is in motion.

Another object is to provide a simplified and durable mechanism embodying certain improvements over the form of device shown in my said pending application, which will appear as the description progresses. In the accompanying drawings I have shown a preferred form of invention subject to modification within the scope of the appended claims without departing from the spirit thereof.

In said drawings,

Fig. 1 is a longitudinal sectional elevation of the propeller mechanism in the plane of the axis of the propeller.

Fig. 2 is a front elevation of the same with the cover plate for the propeller hub removed to show the mechanism within the hub.

Fig. 3 is a rear elevation of the driving and control mechanism partly in section.

Fig. 4 is a transverse section of one of the propeller blades on line 4—4 of Fig. 1.

Fig. 5 is a fragmentary plan of the mechanism partly in section.

The following is a detailed description of the structure and operation of my improved mechanism. Referring to Fig. 1, A is a housing which may be suitably attached to the motor block or to the fuselage of a plane or the like and may include several sections, as at a, b, c, d, e, etc., suitably formed and detachably connected together for the purpose of facilitating the assembly of the mechanism. Enclosed within said housing and secured

drive gear 2 which meshes with and drives a driven gear 3 suitably fixed to a hollow shaft 4 which is spaced from and parallels the shaft 1. Attached to or formed on the outer end of shaft 4 is a hub 5 which supports a plurality of propeller blades 6, 6 etc. and associated parts.

Each of the blades 6 is operatively supported on the housing by means of a stem or shaft 7 which is radially positioned relative to the axis of the hub 5 and the driven shaft 4. The propeller stems 7 are journaled in bearings 8 which are preferably of frictionless character, as shown in Fig. 1. The inner extremities of the stems 7 carry beveled pinions 9 which commonly mesh with a relatively central master gear 10 which has a hollow hub 11 journaled in a bore formed in the outer end of shaft 4.

Oppositely formed helical grooves 12, 12 with a long lead are provided in the bore of hub 11 for receiving the opposite ends of a pin 13 which extends diametrically thru and projects from opposite portions of the periphery of a hollow shaft 14, which is journaled in the hub 11 of gear 10.

The inner end 15 of shaft 14 is journaled and also slidably supported in the hollow shaft 4. A pin 16 is extended diametrically thru the inner end 15 of shaft 14 and its opposite ends extend thru slots 17, 17 forming keyways for said pin, which are provided near the inner end of shaft 4. A flanged plug 18 is threaded into the inner end of shaft 4 to provide a retaining ring for an annular thrust bearing 19 which supports said shaft 4 at its inner end in the housing A.

Bearing 19 is supported by means of a ring 20 secured in position within the housing A by means of a plurality of screws or bolts, as at 21. Intermediate the master gear 10 and the bearing 19 the shaft 4 is additionally supported by means of a frictionless bearing 22 within and suitably supported by the housing A. Intermediate the bearings 19 and 22 a frictionless bearing 23 is provided which encompasses the shaft 4 and has its inner cone 24 fixed at diametrically opposite points to the extremities of pin 16. The

outer cone 25 of bearing 23 is formed so as to provide longitudinal thrust to the shaft 14 by means of the connection of said bearing with the pin 16.

5 The cone 25 is provided with an annular flange 26 having slots 27 therein which slidably engage splines 28 formed on or affixed to the interior of housing A. The member 25 is also provided upon its periphery and 10 inwardly of flange 26 with external threads 29 (preferably double or triple threads) so as to provide for rapid adjustment of the device, as hereinafter described.

15 A ring gear 30 with internal threads 31 corresponding in size, pitch and lead to the threads 29 on members 25 is supported within the housing A by means of bearings 32 and 32' suitably secured to said housing. A rack 33 is provided within the housing for reciprocal movement in a transverse plane for rotating the ring gear 30 to a selected extent at will, said rack being suitably mounted for 20 slidable movement in the housing A.

25 A shaft 34, preferably of tubular form in order to provide light weight, is mounted within the shaft 14, and its inner end is held in the collar 18 as shown. Shaft 34 is slotted at diametrically opposite points throughout its 30 length excepting at its two extremities to permit a relative longitudinal movement of shafts 14 and 34. At this point it will be noted that relative rotation of shafts 4, 15 and 34 is prevented by means of the pins 13 and 16, and a supplemental pin 35 may be 35 provided, as shown in Fig. 1, for this purpose if necessary. Said pins, however, provide means for operatively connecting the shafts 3, 14 and 34.

40 Outwardly of the beveled pinions 9 attached to stem 7 I provide within the hub 5 a radially disposed locking pin 36 associated with each of the propeller blades, the outer ends of said pins being enlarged at 37 and conically formed at their outer extremities to facilitate the seating thereof in correspondingly shaped cavities 38 which are provided in the inner end of each of the blades 6. The inner end of each pin 36 is provided with a block 41, one end of which is squared 45 to slidably engage an end cover plate 42 of hub 5, thereby preventing the rotation of the pin, while the inner end of each block 41 is beveled as and for the purpose hereinafter described.

55 The pins 36 are normally urged into seating engagement with the cavities 38, by means of coil springs 39 carried on said pins within bores 40 in the hub 5, and said springs compress between the bottoms of said bores 60 and the heads 37 of the pins. The outer end of shaft 34 is internally threaded to receive a flange pin 43 by means of which a spider ring 44 is secured to shaft 34 and pin 43 extends substantially outwardly from the 65 spider and thru an orifice provided in the

cover plate 42 and is provided with a retaining nut 45 on the outer end thereof adjacent said cover plate.

A compression spring 46 is mounted on the pin 43 between the end of the shaft 34 and plate 42, thereby normally urging the spider 44 and the shaft 34 inwardly or to the right, as seen in Fig. 1. The inward movement of shaft 44 and associated parts, however, is limited by the nut 45 which engages the cover 70 plate 42. The inner end of shaft 34 is provided with a conical plug 47 adapted for engagement with a cam 48 secured to a rack 49 as by means of screws or pins 50. The racks 33 and 49 which are substantially in the same plane and in parallelism preferably project from one side of the housing A and may be suitably enclosed within an additional housing B secured to the housing A as by means of bolts, as at 51. (See Fig. 3.)

80 Suitably journaled in the auxiliary housing B are a pair of hollow telescoping shafts 52 and 53, the former being inwardly of the latter. One end of shaft 52 has a pinion 54 secured thereto within the housing B which meshes with rack 33, and a corresponding end of shaft 53 has a pinion 57 secured thereto, as by means of set screws 56, within the housing B, which meshes with the rack 49. The opposite ends of shafts 52 and 53 carry hand wheels or handles 55 and 58, respectively, for operating the racks 33 and 49.

85 The operation of the mechanism is as follows:

90 When a pilot or operator desires to change the pitch of the propeller blades 6, 6 etc. while the motor is operating, the control handle 58 is moved in a clockwise direction, as seen in Fig. 5, thus correspondingly rotating the pinion 57 thru the medium of the rack 49 and also 95 rotating the cam 48 into engagement with the tapered plug 47 on the end of shaft 34. The rotation of handle 58 and its shaft 53 as described will move shaft 34 longitudinally and outwardly in the direction of the cover plate 42, thereby causing the spider 44 on the outer end of said shaft to engage the beveled blocks 41. Thus the heads 37 of the locking pins 36 are drawn inwardly against the tension of their springs 39 and from positions of engagement with the cavities 38 in the propeller mounting.

100 The blades 6, 6, tho in such case free to be rotated manually, are incapable of rotation by impingement of the air currents thereon because of their operative connection with shaft 4 thru gears 9 and 10 and pin 16 and the engagement of pin 13 with the helical 105 grooves 12. By means of the gear connection between shaft 4 and shaft 1 the motor continues to drive the propeller with the blades 6 thereon remaining at their established pitch.

110 However, due to the pressure of the air upon the blades 6 and the resultant tendency 115

to rotate the beveled gears 9, 9 etc. and 10, the grooves 12 are so inclined as to urge the pin 13 backwardly to overcome or resist the tendency to rotate the beveled gear. Thus 5 the shaft 14 and the pin 16 exert a thrust to the right, as seen in Fig. 1, on the bearing 23. It will be noted that the frictionless bearing 23 not only serves as a thrust bearing for the shaft 14 but it additionally serves as an 10 annular bearing by means of which the parts of the mechanism are rotated for changing the pitch of the gears.

When the heads 37 of the locking pins 36 are seated in the cavities 38 said pins serve 15 to positively lock the blades at a predetermined angle. When the heads 37 are disengaged from the cavities 38 the control wheel 55 is rotated in a clockwise direction, thereby correspondingly rotating the gear 31, as 20 seen in Fig. 3, by means of pinion 54 and rack 33. The rotation of gear 31 serves to move the ring 25 rearwardly due to the threaded connection of said gear with said ring. The ring 25 is prevented from rotation by means 25 of the splines 28.

By reference to Fig. 1 it will be observed that because of the structural connection of the bearing 23 with the pin 16 any movement of ring 25 rearwardly will correspondingly 30 move shaft 14 longitudinally of shaft 4. The pin 13 being fixed in the shaft 14 and having its ends engaging the helical grooves 12 in hub 11 of gear 10 will, when the shaft 14 moves rearwardly, engage and rotate gear 10 35 in a clockwise direction, as seen from the rear of Fig. 1, thereby changing the angle of the blades 6 thru the operative connection of gears 9 and 10.

Tho not shown in the drawings or described herein, the operating members 55 and 58 may be provided with suitable ratchets or other devices of conventional type to prevent their operation except at the will of the operator and to hold them in positions to 45 which they have been moved by the operator.

When the angle of the blades 6 has been changed as described, the control handle 58 is then moved by the operator in a reverse or counter-clockwise direction, as seen in 50 Fig. 5, thereby, thru the medium of the gear 54 and the rack 33, retracting the cam 48 from engagement with the plug 47. Spring 46 is then free to move the shaft 43 carrying the spider 44 rearwardly, disengaging the 55 beveled blocks 41, thereby permitting the heads 47 to seat in certain of the cavities 38, which positively locks the blades 6 at the desired angle.

What I claim is:

60 1. A propeller mechanism comprising in combination a plurality of propeller blades together rotatable about a common axis and independently rotatable on different axes for changing the pitch thereof, a driving shaft, bevel gears rotatably connecting all of said

propellers for common rotation with said shaft, means for locking said propellers against adjusting as to pitch, and means including a shaft axially disposed relative to the propeller longitudinally extensible for 70 engaging said locking means for unlocking said blades, and relatively telescoping means rotatably adjustable for changing the pitch of said propeller at will.

2. A propeller mechanism comprising in combination a plurality of propeller blades together rotatable about a common axis and independently rotatable on different axes for changing the pitch thereof, a driving shaft, bevel gearing for rotatably connecting all of 75 said propellers for common rotation with said shaft, plungers radiating from the axis of the propeller shaft engaging and for locking said blades against adjusting as to pitch, and a pair of shafts telescoping said driving shaft, one of said shafts adapted to engage and retract said plungers for respectively unlocking the propeller blades and the other shaft connected with said gears for changing 80 the pitch of said propellers at will, said last mentioned means including independent devices connected respectively with and for manually operating said shafts.

3. A propeller mechanism comprising a 85 housing, driving and driven shafts mounted therein and operatively connected, a rotatable propeller hub fixed to said driven shaft, a plurality of propeller blades radially disposed and adjustable as to pitch on said hub, bevel gearing connecting said blades with 90 said driven shaft to permit the simultaneous rotation of the propellers when power is applied from the driving shaft, simultaneously operable locking devices enclosed by said hub 95 for locking said blades against rotation on said hub during the rotation thereof, and a pair of shafts telescoping said driven shaft and slidably adjustable thereon for respectively engaging and retracting said locking devices for unlocking the blades to permit 100 the adjustment thereof, and for thereafter rotating the blades thru said gears to a common extent for changing their pitch.

4. A propeller mechanism as characterized 105 in claim 3, including cooperating means on one of said axially adjustable members and on said locking means for retracting the locking means.

5. A propeller mechanism comprising a 110 housing, a propeller unit rotatable on said housing and including a central body and a plurality of radially disposed blades rotatable thereon for varying their pitch, said unit having a shaft supported in said housing, bevel gearing operatively connecting said propeller shaft with said blades, a drive shaft journaled in said housing operatively connected with said propeller shaft, and a pair of telescoping 115 shafts axially adjustable in said propeller shaft and rotatable therewith, radially dis-

posed plungers in said propeller body for locking said blades normally against adjustment, and means externally of said housing and connected respectively with said telescoping shafts and with said propeller blades for manually unlocking and adjusting the pitch of said blades while the propeller unit is rotated.

6. A propeller mechanism comprising a housing, a drive shaft journaled therein, a hub having a shaft extended therefrom journaled also in said housing, gearing connecting said shafts, a plurality of propeller blades rotatably mounted on the periphery of said hub and having shafts journaled in said hub, beveled gearing operatively connecting the shafts of said blades with said hub shaft, means externally of said housing for rotating said gearing so as to correspondingly rotate and change the pitch of said blades, plungers radially disposed in said hub from and relative to the axis of said hub for locking engagement with said blades, a shaft telescopically held in said hub and manually operable from the exterior of said housing for longitudinal movement, and cooperating devices on the inner extremities of said plungers and the adjacent end of said telescoping shaft for simultaneously and correspondingly retracting and unlocking said plungers from the said blades to permit the rotation of the blades on the hub thru the operation of said gears to change the pitch thereof.
